MEANS FOR FLANGING THE EDGE OF A
ROUND OPENING

Mathäus Wiest, Einswarden i. O., Germany, assignor to L. Schuler A. G., Goppingen, Germany

Application June 18, 1937, Serial No. 148,990
In Germany April 4, 1935

8 Claims. (Cl. 153—29)

An application was filed in Germany on the 4th April, 1935 (patent not yet granted).

This invention relates to improvements in means for flanging the edge of a round opening in a sheet metal blank in which the edge of the metal sheet is clamped on a work table by means of a movable clamping member is pressed, by a rotating flanging tool introduced in axial direction into the opening, against an exchangeable flanging ring formed by said clamping device, and the inner diameter of which corresponds to the outer diameter of the flange to be raised from the material. The clamping device performs two functions, namely, firstly clamping the workpiece 15 and secondly acting as an abutment for the flange to be raised. In order to centre or position the workpiece with regard to the tool, a centering device is provided, which is caused to enter the pre-formed openings in the workpiece and move 20 the workpiece into the required position relatively to the tool before the latter is operated.

For flanging the edge of a circular opening in metal sheet material, forging, pressing and drawing methods have been in use. The two first 25 mentioned operations, namely flanging by forging or pressing have hitherto been carried out manually by skilled workmen. These operations were comparatively expensive and involved a considerable amount of time. Flanging by drawing can be carried out within a much shorter time, but comparatively expensive tool sets have 30 to be employed, and as a rule, a separate set is required for every diameter of the opening.

An object of the invention is to provide a novel 35 construction of the centering device which co-operates with a known flanging tool. The centering device which may be used independently is, according to the invention, resiliently mounted in the clamping device so that it is moved during 40 the clamping operation into the opening of the workpiece, and is then gradually moved from the opening from the initial centering position by the flanging head.

In a known flanging device, the workpiece is 45 centered by a centering pin rigidly mounted in the tool, and a combined tool is used which first cuts a circular opening in a disc blank and subsequently raises the edge portion of the opening. In this known device, the workpiece is only 50 incompletely clamped at two points. By the use of the present invention, the raising of the edge is effected in a very efficient manner and without any waste within the shortest possible time owing to the fact that the workpiece is clamped along 55 an annular surface very firmly and without any

possibility of creasing or bending the workpiece. This annular clamping of the workpiece is particularly important with very light or thin sheet metal and renders it possible to form in light sheet metal circular holes and flange the edges 5 of these holes, whereby the stiffness and resistance of the material is considerably increased.

A further object of this invention is to provide an improved flanging head comprising a plate having spiral slots therein, a second plate having 10 radial slots therein and rotatable relatively to the first plate and vertical flanging rollers rotatably mounted on bolts insertable into the crossing points between the spiral and radial slots. By relative rotation between the plates, the flanging 15 rollers may be moved relatively to one another to adjust them to the diameter of the particular opening to be flanged and, by tightening the bolts in the slots, the plates are fixed in the 20 adjusted position.

It is known in connection with combined 25 punching and bending tools, to mount the pressing members by means of co-operating radial and spiral slots. This known arrangement, however, is used for moving the pressing members firmly 30 towards the center of the workpiece, whilst the tool stands still. It will thus be seen that the known arrangement is used for a different purpose in the present invention.

The accompanying drawing shows, by way of 35 example, one construction of a flanging means embodying the invention.

Fig. 1 is an elevation partly in section of the 40 complete flanging device including its drive,

Fig. 2 shows in sectional elevation one half of 45 the flanging device proper, and

Fig. 3 shows the flanging head, not including 50 the flanging rollers.

Figs. 2 and 3 are drawn to a larger scale than 55 Fig. 1.

The workpiece *a* having a circular opening rests upon a table *b* having a corresponding but slightly larger opening. In an annular recess of the table lies a bearing ring *c*. Above the ring *c* is located a flanging ring *d* provided with a ring *e*, which latter serves both as a flanging ring proper and for clamping the workpiece *a*. The flanging ring *d* is mounted upon a spindle *g* which latter is operated by means of a hand wheel *f*. The spindle *g* is provided with a screw-thread and 60 engages a threaded socket formed in a yoke-shaped portion *h* of the machine frame extending above the work-table *b*. On turning the hand-wheel *f*, the spindle *g* is screwed into or out of the socket *h*, whereby the flanging ring *d* 65

is raised from, or lowered towards, the work-piece *a*. Within the flanging ring *d* is resiliently mounted a centering plate *i*, said plate being in the construction shown suspended from the ring by means of helical springs, the said ring having a depending pin *d'* on which the plate *i* can slide vertically. With this construction the flanging ring *d* and the centering plate *i* are rotated with the spindle *g* and on contacting the work-piece may impart a partial rotation to the latter; although this does not in any way affect the actual flanging operation, it is to be understood that if desired, the construction may be in known manner suitably modified, so that the spindle *g* and the parts carried thereby do not partake in the rotation of the hand-wheel *f*. The centering plate has a conical surface which centers the workpiece *a*. *k* indicates a flanging head carried by a rotatable shaft *m* which latter is driven by means of a pair of bevels *p*, *q*, a shaft *o* and a belt pulley *n*. The shaft *m* is longitudinally movable in the bevel *q*. The flanging head *k* comprises two plates *t* and *u*, the plate *t* having radial slots *r* and the plate *u* having co-operating spiral slots *s*. The flanging rollers *v* are freely rotatably mounted on vertical bolts *l* passing through the two slots, which bolts *l* are each formed with a flange or collar *2* at the upper end thereof to prevent the sliding off of the rollers *v*, and are screw-threaded at their lower end for the purpose of enabling a securing nut *3* to be screwed on to the portion protruding through the underside of the slots *r* and *s*. After the two plates have been adjusted for the required opening by moving one of the plates relatively to the other, the said bolts are tightened whereby the said plates are fixed in the adjusted position.

The shaft *m* is supported in the bearing *11* and carries through the interposition of a ball bearing a muff *w* which is longitudinally slideable with, but does not take part in the rotation of, the shaft *m*. The said muff *w* has inclined teeth *x* co-operating with corresponding teeth of a swingable but axially immovable muff *y* resting on the bearing *11*. The rotation of the muff *w* is prevented by a pin *10* fixed to the said muff and engaging a hole in the said bearing *11*. To enable the device to be used for flanging the edges of openings of various diameters, the rings *c*, *d* and *e* are exchangeable. The inner diameter of these rings always corresponds to the outer diameter of the flange to be produced.

Z is a hand lever connected to the muff *y* by means of which the latter can be swung for the purpose of raising the muff *w*, with the shaft *m* as hereinafter referred to.

The operation of the apparatus is as follows:

After the workpiece *a* has been placed upon the work table *b*, the flanging ring *d* is lowered into the work table *b* by turning the hand wheel *f*. During this operation, the centering plate *i* enters the opening in the workpiece *a* and centers the workpiece. The ring *e* subsequently comes into contact with the workpiece *a* and clamps the latter against the work table *b*. The muff *y* is then swung by means of the lever *z* thereby raising the flanging head *k*. The flanging rollers *v* come into contact with the edge of the workpiece *a* which up to that moment was bearing against the conical surface of the centering plate *i* and gradually raise the edge portion during the further upward movement of the flanging head *k*. At the same time, the centering plate *i* is forced by the flanging head *k* upward from the opening in the workpiece.

When it is desired to adjust the relative position of rollers *v*, the nuts *3* are loosened, the two plates *t* and *u* are turned relatively to one another, so that the bolts *l*, and the rollers *v* carried thereby, approach, or move away from, the axis of the flanging head *k*. When the correct position has been attained the securing nuts *3* are again tightened on the bolts to retain the plates *t* and *u* and thus the bolts *l* in this position.

A number of advantages are attained by the use of the improved flanging means in accordance with the invention.

Firstly owing to the fact that the flanging ring serves both for flanging and for clamping the workpiece, a separate clamping device for holding the workpiece in co-operation with the work table *b* is entirely dispensed with. The combination of the centering device with the movable member of the clamping device, avoids the necessity for a separate working operation for centering the workpiece and consequently saves a considerable amount of time, inasmuch as the movement of the movable part of the clamping device required for clamping the workpiece is utilised for simultaneously introducing the centering device into the workpiece and for centering the latter. The resilient mounting of the centering device enables the flanging head to enter the workpiece without hindrance.

Secondly a simplified construction is obtained inasmuch as it is possible to employ the same flanging tool for openings of various diameters by merely exchanging the exchangeable portions of the clamping device and adjusting the flanging rollers in the flanging head to correspond to the different diameters. It is therefore not necessary to employ a set of tools for each diameter of opening. The main advantage of the invention, however, lies in the considerable shortening of the time required for carrying out the flanging operation, as compared with that used in flanging by pressure or forging. In order to flange the edge of an opening by the usual pressing process, three working operations are required together with two intermediate heatings, whilst by the use of the improved flanging means only two working operations and one intermediate heating are needed. With the ordinary pressing process about twenty minutes are required for doing the same work which can be carried out by means of the present invention in twenty seconds, the employment of unskilled operators only being necessary.

It will be understood that the improved flanging means may be used for the formation of practically any kind of flange, such as Z-shaped flanging in which the flanges have an irregular surface comprising surface portions intersecting at right or obtuse angles, as the shape of the flange depends only on the shape of the flanging rollers and the ring mounted in the movable clamping device.

I claim:

1. Means for flanging a circular opening in a sheet metal blank comprising in combination: a clamping table having a circular opening; a movable clamping member co-operating with said clamping table and likewise having a circular opening; a centering device resiliently mounted in said movable clamping member, and a rotatable and axially movable flanging head provided with flanging rollers, said centering device being so constructed and mounted in said clamping member that upon movement of the movable clamping member towards the clamping table,

said centering device enters first the circular opening in the blank and centers the blank, whereupon the clamping member clamps the blank against the clamping table, said flanging head being so constructed that on movement towards and into the blank, it will lift the centering member from the blank, said movable clamping member having a surface adapted to act during the flanging operation as an abutment cooperating with the flanging rollers.

2. Means for flanging a circular opening in a sheet metal blank comprising in combination: a clamping table having a circular opening and an exchangeable bearing ring; a movable clamping member having an exchangeable flanging ring the lower surface of which co-operates with the exchangeable ring of the clamping table for clamping the workpiece, the inner side of said exchangeable clamping ring serving as an abutment against which the flange is pressed; a centering member having a conical centering surface resiliently mounted in said clamping member and so located that on moving the movable clamping member towards the clamping table said centering member will first center the workpiece before the clamping member clamps the workpiece against the clamping table, and a flanging head comprising rotatable flanging rollers, so constructed that upon movement of the flanging head into the blank, said flanging head will move said centering device out of contact with the workpiece and subsequently form the flange by pressing the edge of the workpiece against the side of the exchangeable ring of said movable clamping member.

3. Means for flanging a circular opening in a sheet metal blank comprising in combination: a clamping table; a movable clamping member co-operating with said clamping table for clamping the workpiece, both said clamping table and said movable clamping member having circular openings of the same diameter; a centering member resiliently mounted in said movable clamping member, said centering member coming during movement of the movable clamping member towards the clamping table into contact with the workpiece and centering the latter before the two clamping members grip the workpiece; and a flanging head comprising two plates, one plate having radial slots and the other plate having spiral slots, said plates being relatively turnable with regard to each other; and flanging rollers mounted upon vertical bolts inserted into the points of crossing of corresponding radial and spiral slots of the plates.

4. Means for flanging the circular opening in a sheet metal blank comprising in combination: a stationary clamping table having an exchangeable bearing ring; a movable clamping member co-operating with said clamping table for clamping the workpiece and having an exchangeable flanging ring the lower surface of which clamps the workpiece and the inner side of which serves as an abutment during the flanging operation; a centering member resiliently mounted in said movable clamping member for centering the workpiece; a flanging head having flanging rollers; and means for moving said movable clamping member towards the clamping table comprising a stationary frame member; a spindle mounted therein and carrying said movable clamping member and a hand wheel by the rotation of which said spindle and clamping member are moved up and down.

5. Means for flanging the circular opening in

a sheet metal blank comprising in combination: a clamping table having a circular opening and an exchangeable bearing ring around said opening; a clamping member for clamping in cooperation with said clamping table a blank, said movable clamping member having an exchangeable flanging ring the lower surface of which serves for clamping the workpiece and the inner side of which serves as an abutment during the flanging operation; a conical centering disc suspended by means of springs from said clamping member; means for moving said movable clamping member towards the clamping table comprising a spindle and a hand wheel for moving said spindle up and down; a rotatable flanging head comprising a plate having spiral slots, a second plate rotatable relatively to the first mentioned plate and having radial slots; and rotatable flanging rollers mounted upon bolts inserted into the crossing points between said slots; and means for raising said flanging head into the opening of the blank, said centering member being so located with regard to said movable clamping member and said clamping head that upon downward movement of said clamping member, said centering member will enter the opening in the blank and centre the blank before the latter is gripped between the movable clamping member and the clamping table, and that upon upward movement of the flanging head into the opening of the blank, said centering member will be raised by the flanging rollers out of contact with the workpiece.

6. In means for flanging the edge of a round opening in a sheet metal blank of the kind referred to, including a clamping table; a movable clamping member for the blank cooperating with said table; and a movable flanging head associated therewith, the provision of: a centering device resiliently mounted in said movable clamping member, said centering device being so constructed and located that, on movement of said clamping member in a blank-clamping direction, said centering device is also moved into the opening in said blank to centre the blank and said flanging head being so constructed that on subsequent movement thereof to form the flange, said centering device is moved from the initial centering position by said flanging head.

7. In means for flanging the edge of a round opening in a sheet metal blank of the kind referred to, including a clamping table; a movable clamping member for the blank co-operating with said table and a movable flanging head associated therewith, the provision of: a centering device having a conical centering surface, said centering device being resiliently mounted in said movable clamping member, said centering device being so constructed and located that, on movement of said clamping member in a blank-clamping direction, said centering device is also moved into the opening in said blank to centre the blank and said flanging head being so constructed that on subsequent movement thereof to form the flange, said centering device is moved from the initial centering position by said flanging head.

8. In means for flanging the edge of a round opening in a sheet metal blank, of the kind referred to, including a clamping table and a movable clamping member for the blank co-operating with said table, the sub-combination of: a centering device resiliently mounted in said movable clamping member and a movable flanging head associated therewith, said flanging head compris-

ing two relatively turnable plates, one plate having spiral slots and the other having radial slots, and rotatable flanging rollers mounted on fixable bolts inserted in the points of crossing of corresponding radial and spiral slots in said plates, said centering device being so constructed and arranged that, on movement of said clamping member in a clamping direction, said centering

device is moved into the opening in said blank to centre the latter, and said flanging head being so constructed that on movement thereof towards the blank said centering device is moved with respect to said clamping member out of the initial centering position.

MATTHÄUS Wiest.
